UNITED STATES PATENT OFFICE

ROBERT L. BLANCHARD, OF NEW YORK, N. Y., ASSIGNOR TO VAN KANNEL REVOLVING DOOR COMPANY, OF NEW YORK, N. Y., A CORPORATION OF NEW JERSEY

SPEED REGULATOR FOR REVOLVING DOORS

Application filed October 15, 1930. Serial No. 488,976.

This invention relates to revolving doors, and has particular reference to a mechanism for controlling the speed of rotation thereof.

While revolving doors possess many advantages over swinging doors, they are open to the one serious objection that there is no effective means for limiting their speed of rotation, thus allowing them to be spun or revolved so rapidly that users thereof in some instances are compelled to either wait until the speed is gradually reduced by loss of momentum or else risk possible injury in attempting to manually retard the speed of rotation of the door.

It is, therefore, the broad object of the present invention to provide a mechanism which functions to preclude the rotation of a revolving door above a predetermined speed while permitting of a free turning of the door at any speed less than said predetermined speed.

The invention further comprehends a speed controlling mechanism for a revolving door, which serves to retard the speed of rotation thereof when the speed reaches a predetermined maximum, without actually bringing the door to a stop and in which said mechanism instantly functions to render the speed retarding means inactive when it drops below the predetermined maximum.

In view of the fact that revolving doors are usually mounted to admit of shifting movement of the same laterally to a folded out-of-the-way position, the present invention comprehends a speed controlling means which does not interfere with the shifting movement.

As a further object, the invention resides in the provision of a speed controlling mechanism for revolving doors which includes means by virtue of which the maximum speed may be regulated.

Other objects of the invention reside in the comparative simplicity of construction and mode of operation of the mechanism, the economy with which it may be produced and installed and the general efficiency derived therefrom.

With the above recited and other objects in view, reference is had to the following de-

scription and accompanying drawings, in which there is exhibited one example or embodiment of the invention, while the claims define the actual scope of the same.

In the drawings:

Figure 1 is a fragmentary plan view of a revolving door equipped with a speed controlling mechanism constructed in accordance with the invention.

Figure 2 is a fragmentary vertical sectional view taken approximately on the line indicated at 2-2 in Figure 1.

Figure 3 is a vertical sectional view taken approximately on the line 3-3 of Figure 1, illustrating the mechanism in its normal inactive condition.

Figure 4 is a similar view illustrating the mechanism in its active position for retarding the speed of rotation of the door.

Figure 5 is an enlarged transverse fragmentary sectional view taken approximately on the line indicated at 5-5 in Figure 1.

Figure 6 is a fragmentary plan view illustrating the door carriage shifted laterally with respect to the speed controlling mechanism.

Referring to the drawings by characters of reference, A designates generally the usual carriage, from which the revolving door B is suspended for rotation on a depending shaft C, the carriage being provided with rollers D movable over the overhead tracks E extending transversely of the opening in which the door is mounted to revolve, whereby the leaves of the door may be folded and the door bodily shifted to one side of the doorway.

In order to provide means for retarding the speed of rotation of the door, any suitable form of brake may be employed, which in the present instance is generally indicated by the reference character F, consisting of a brake drum 10 with which an internal expanding brake band 11 is designed to coact. The brake drum 10 obviously is secured to the revolving shaft C which carries the door, while the brake band 11 is suitably mounted on the carriage A. An arm 12 projects laterally from the carriage and is movable to control the application of the brake band to

the braking surface of the drum 10, for the purpose of retarding the speed of rotation of the door B.

In order to provide means operable by the rotation of the door B when it reaches a predetermined rate of speed for effecting the application of the brake, a governor is employed, which is designated generally by the reference character G, and said governor is installed alongside of the carriage tracks E and is enclosed in a casing or housing 14. The governor is of the ordinary centrifugal type, including a stationary shaft 15 having a non-slidable rotary head 16 and a slidable rotary head 17 with weight arms 18 fulcrumed to the non-slidable head 16 and provided at the free ends with weights 19, while links 20 are connected respectively to the weight arms 18 and the slidable head 17, so that upon rotation of the head at a given speed, the weight arms 18 will move radially outward by centrifugal force to slide the slidable head 17 toward the non-slidable head 16. Rotation is imparted in the present instance to the governor head 16 from the revolving door by a friction sheave 21, which is suitably secured to the revolving door shaft C and which engages with a friction wheel 22 mounted within the governor casing or housing 14, while the friction wheel 22 in turn engages with a friction sheave 23 secured to the head 16. The periphery of the friction wheel 22 is normally urged into contact with the grooved periphery of the friction sheave 21 through a slot 24 in the side of the casing or housing 14, by means of a coiled contractile spring 25 which is secured respectively at its opposite ends 26 and 27 to the casing and to the free end of a bracket arm 28 fulcrumed at 29 to the casing, the friction wheel 22 being mounted for rotation on a depending spindle 30 of the bracket arm. The bracket arm is guided and limited in its movement by a guide strap 31 on the casing or housing 14. The governor shaft 15 is secured to and depends from a slide 32, which slide is in turn carried for longitudinal adjustment by the bracket arm 28 and is adjusted by an adjusting screw 33 which functions to insure the proper frictional engagement of the grooved periphery of the friction sheave 23 with the friction wheel 22, said adjustment also functioning to compensate for wear on the engaging peripheries of the friction wheel and sheave 22 and 23.

The means for moving the brake actuating arm 12 consists of a lever 35 which is fulcrumed as at 36 on a projecting ear 37 of the casing and which extends inwardly through a slot 38 in the casing or housing with its inner end 39 disposed in the path of movement of the terminal 40 of an adjustable actuating screw 41 which is threaded through one arm 42 of a bell crank 43 fulcrumed as at 44 on an upstanding bracket 45 of the bot-

tom wall of the casing or housing 14. A coiled contractile spring 46 has its opposite extremities 47 and 48 respectively connected with the inner end 39 of the lever 35 and the casing or housing 14, to normally swing said end 39 into contact with the extremity 40 of the adjustable screw 41. The remaining arm 48 of the bell crank 43 is linked by a link 49 to one arm of the bell crank 50 which is fulcrumed as at 51 to a bracket 52 within the casing or housing 14, and the opposite arm of the bell crank 50 is connected by a rod 53 to the core 54 of a solenoid 55. The solenoid 55 is controlled by a mercury switch 56 of any of the conventional types now on the market. The mercury switch is in turn carried by the arm 57 of a bell crank 58 which is fulcrumed as at 59 to a bracket 60 within the casing or housing 14. The bell crank is rocked through the medium of the engagement of the forked terminal 61 of its remaining arm 62, which forked terminal is provided with trunnions 63 engaging in the annular peripheral groove 64 of the slidable head 17 of the governor. In order to regulate the speed at which the governor will function to rock the bell crank 58 for the purpose of closing the circuit to the solenoid, a scale beam 65 is secured to the arm 57 and is provided with an adjustable counterweight 66.

In use and operation, it will be assumed, for the purpose of illustration, that the counterweight 66 is set at a point to control the governor G, so that a speed of rotation of the revolving door at the rate of fifteen revolutions per minute will cause the slidable head 17 to move upwardly a sufficient distance to tilt the switch 56 to close the circuit. It thus follows that rotation of the door B at the rate of fourteen revolutions per minute or any speed therebelow will not be sufficient to rock the bell crank 62 and, hence, the door will revolve freely at all speeds up to and including fourteen revolutions per minute. If an attempt is made to revolve the door at fifteen or more revolutions per minute, the governor G will instantly function to rock the bell crank 58 and tilt the switch 56 sufficient to effect the closing of the circuit to the solenoid. This immediately energizes the solenoid and draws inwardly on the core 54 and rod 53 connected thereto and through the medium of the bell cranks 50 and 43 swings the lever 35 to move the actuator arm 12 for expanding the brake band 11 against the braking surface of the brake drum 10 to offer a resistance to the turning movement of the door and retard its revolutionary movement. Instantly, the action of the brake in retarding the speed of rotation of the door permits the weighted governor arms 18 to slide the slidable head 17 downwardly and rock the bell crank 58 and switch 56 to break the circuit to the solenoid and de-energizes the same. The spring 46 immediately swings the lever

35 to its normal position and releases the braking force of the brake. It thus follows that the mechanism described functions to restrict the speed at which a revolving door 5 may be rotated, thereby positively precluding the possibility of spinning or rapidly rotating the same above a speed conducive of safety to the users thereof. It is also apparent that the maximum speed may be regulated by a simple adjustment of the weight 66 on the scale beam 65, it being obvious that the greater distance the weight 66 is moved from the bell crank arm 57, the higher the maximum speed possible will obtain, and vice 10 versa. The adjustment screw 41 functions to permit of a regulation of the braking force to be applied. It is also apparent that due to the mounting of the friction sheave 21 and friction wheel 22, that the mechanism 15 for controlling the speed of the door will not interfere with the lateral shifting of the door when folded, as the sheave 21 will cam the friction wheel 22 inwardly when it is moved from the open laterally shifted folded 20 position to the active position.

While there has been illustrated and described a single and preferred embodiment of the invention, no limitation is necessarily intended to the precise structural details, as 25 variations and modifications which properly fall within the scope of the claims may be resorted to when desired.

What is claimed is:

1. The combination of a revolving door 35 and means actuated by a force that is independent of the force applied to the door for revolving the same and rendered active by rotation of said door at a predetermined rate of speed for retarding the speed of rotation 40 of said door.

2. The combination with a revolving door of normally inactive means actuated by a force that is independent of the force applied to the door for revolving the same for retarding the turning movement of the door and means operable by the rotation of the door at a predetermined rate of speed for rendering said first means active.

3. The combination with a revolving door 50 of a normally inactive brake actuated by a force that is independent of the force applied to the door for revolving the same for retarding the turning movement of the door and governor controlled means operable by the 55 rotation of the door at a predetermined rate of speed for rendering said brake active.

4. The combination with a revolving door of normally inactive means actuated by a force that is independent of the force applied 60 to the door for revolving the same for retarding the turning movement of the door, means operable by the rotation of the door at a predetermined rate of speed for rendering said first means active and means for regulating 65 said second means to vary the determined

rate of speed at which said second means will function to render the first means active.

5. The combination with a revolving door of normally inactive electro-magnetically actuated brake means for retarding the turning movement of the door, a controlling switch for said electro-magnetically actuated brake means and a door actuated governor for controlling said switch.

6. The combination with a revolving door of normally inactive electro-magnetically actuated brake means for retarding the turning movement of the door, a controlling switch for said electro-magnetically actuated brake means, a door actuated governor for controlling said switch and a counterweight for regulating said governor.

7. In a revolving door, a brake actuated by a force independent of that applied to the door for revolving the same and effective to exert a force to retard the turning movement of the door, means normally holding said brake inactive and mechanism operable by the rotation of said door at a predetermined speed to render said brake effective.

8. A device for controlling the speed of rotation of a revolving door, including a normally inactive brake means operable when actuated to prevent rotation of the door above a predetermined maximum, and mechanism actuated by a force independent of that applied to the door for revolving the same and rendered active by rotation of the door at said predetermined speed for rendering the brake means active.

9. A device for controlling the speed of rotation of a revolving door, including brake means actuated by a force independent of the force applied to the door for turning the same and functioning when active to prevent rotation of the door above a predetermined maximum, and mechanism operable by rotation of the door at and below said predetermined speed for respectively rendering the brake means active and inactive.

10. A device for controlling the speed of rotation of a revolving door, including a normally inactive brake means actuated by a force independent of the force applied to the door for turning the same and functioning when actuated, to retard the rotation of the door and mechanism operable by rotation of the door at said predetermined speed for rendering the brake means effective.

11. A device for controlling the speed of rotation of a revolving door, including a normally inactive brake means operable when actuated to retard the rotation of the door and mechanism operable by rotation of the door at said predetermined speed for rendering the brake means effective, said mechanism including an electro-magnet operatively connected with the brake means and adapted when energized to effect the application of said brake means, a switch for

controlling the electro-magnet and a centrifugal governor operable by rotation of the door when revolved at said predetermined rate of speed for operating the switch to 5 energize the electro-magnet.

12. A device for controlling the speed of rotation of a revolving door, including a normally inactive brake means operable when actuated to retard the rotation of the door 10 and mechanism operable by rotation of the door at said predetermined speed for rendering the brake means effective, said mechanism including an electro-magnet operatively connected with the brake means and adapted when energized to effect the application of 15 said brake means, a switch for controlling the electro-magnet, a centrifugal governor operable by rotation of the door when revolved at said predetermined rate of speed 20 for operating the switch to energize the electro-magnet and means for regulating the governor to vary the speed of rotation of the door, at which said governor functions.

13. A device for controlling the speed of 25 rotation of a revolving door, including a normally inactive brake means operable when actuated to retard the rotation of the door and mechanism operable by rotation of the door at said predetermined speed for rendering the brake means effective, said mechanism including an electro-magnet operatively connected with the brake means and adapted when energized to effect the application of 30 said brake means, a switch for controlling the electro-magnet, a centrifugal governor operable by rotation of the door when revolved at said predetermined rate of speed 35 for operating the switch to energize the electro-magnet and an adjustable weight for regulating the governor to vary the speed of 40 rotation, at which the governor functions.

14. A device for regulating the maximum speed of rotation of a revolving door, including an electro-magnetically controlled 45 brake and a switch for actuating said electro-magnetically controlled brake, said switch operable by the speed of rotation of the door.

15. A device for controlling the speed of rotation of a revolving door, including a normally inactive brake means operable when 50 actuated to retard the rotation of the door and mechanism operable by rotation of the door at said predetermined speed for rendering the brake means effective, said mechanism including an electro-magnet operatively connected with the brake means and adapted when energized to effect the application of 55 said brake means, a switch for controlling the electro-magnet, a centrifugal governor operable by rotation of the door when revolved at said predetermined rate of speed 60 for operating the switch to energize the electro-magnet and means for transmitting rotary motion to said governor consisting of 65 a friction sheave on the door shaft, a fric-

tion sheave on the governor and a friction wheel respectively engaging said sheaves.

16. A device for controlling the speed of rotation of a revolving door, including a normally inactive brake means operable when 70 actuated to retard the rotation of the door and mechanism operable by rotation of the door at said predetermined speed for rendering the brake means effective, said mechanism including an electro-magnet operatively connected with the brake means and adapted when energized to effect the application of 75 said brake means, a switch for controlling the electro-magnet, a centrifugal governor operable by rotation of the door when revolved at said predetermined rate of speed 80 for operating the switch to energize the electro-magnet, means for transmitting rotary motion to said governor consisting of a friction sheave on the door shaft, a friction sheave on the governor and a friction wheel respectively engaging said sheaves and tensioned means for urging the friction wheel 85 against the sheave on the door shaft.

17. A device for controlling the speed of rotation of a revolving door, including a normally inactive brake means operable when actuated to retard the rotation of the door and mechanism operable by rotation of the door at said predetermined speed for rendering the brake means effective, said mechanism including an electro-magnet operatively connected with the brake means and adapted when energized to effect the application of 90 said brake means, a switch for controlling the electro-magnet, a centrifugal governor operable by rotation of the door when revolved at said predetermined rate of speed 95 for operating the switch to energize the electro-magnet, means for transmitting rotary motion to said governor consisting of a friction sheave on the door shaft, a friction sheave on the governor and a friction wheel respectively engaging said sheaves, tensioned means for urging the friction wheel 100 against the sheave on the door shaft and means for advancing the governor sheave 105 against the friction wheel.

18. A device for controlling the speed of rotation of a revolving door, including a normally inactive brake means operable when actuated to retard the rotation of the door and mechanism operable by rotation of the door at said predetermined speed for rendering the brake means effective, said mechanism including an electro-magnet operatively connected with the brake means and adapted when energized to effect the application of 110 said brake means, a switch for controlling the electro-magnet, a centrifugal governor operable by rotation of the door when revolved at said predetermined rate of speed 115 for operating the switch to energize the electro-magnet, means for transmitting rotary motion to said governor consisting of a friction 120 sheave on the door shaft, a friction sheave on the governor and a friction wheel respectively engaging said sheaves, tensioned means for urging the friction wheel against the sheave on the door shaft and means for advancing the governor sheave 125 against the friction wheel.

19. A device for controlling the speed of rotation of a revolving door, including a normally inactive brake means operable when actuated to retard the rotation of the door and mechanism operable by rotation of the door at said predetermined speed for rendering the brake means effective, said mechanism including an electro-magnet operatively connected with the brake means and adapted when energized to effect the application of 130 said brake means, a switch for controlling the electro-magnet, a centrifugal governor operable by rotation of the door when revolved at said predetermined rate of speed for operating the switch to energize the electro-magnet, means for transmitting rotary motion to said governor consisting of a friction sheave on the door shaft, a friction sheave on the governor and a friction wheel respectively engaging said sheaves, tensioned means for urging the friction wheel against the sheave on the door shaft and means for advancing the governor sheave against the friction wheel.

- tion sheave on the door shaft, a friction sheave on the governor and a friction wheel respectively engaging said sheaves, tensioned means for urging the friction wheel against the sheave on the door shaft, means for advancing the governor sheave against the friction wheel and a common mounting for said friction wheel and governor sheave.
19. In a revolving door of the type which includes a laterally shiftable carriage from which the door is suspended for rotation, a device for regulating the maximum speed of rotation of the door including a normally inactive brake means carried by the door carriage and adapted when actuated to retard rotation of the door, mechanism mounted on a stationary support operable by rotation of the door at a predetermined speed for rendering the brake means active and coacting means for transmitting motion from the door to said mechanism.
20. A device for controlling the speed of rotation of a revolving door, including a normally inactive brake means actuated by a force independent of the force applied to the door for turning the same and functioning when actuated, to prevent rotation of the door above a predetermined maximum, mechanism operable revolving the same and by rotation of the door at said predetermined speed for rendering the brake means active and means for instantly rendering the brak-

ing mechanism ineffective, when the speed falls below the predetermined maximum.

21. A device for controlling the speed of rotation of a revolving door, including brake means actuated by a force independent of the force applied to the door for turning the same and functioning when active to prevent rotation of the door above a predetermined maximum, mechanism operable by rotation of the door at and below said predetermined speed for respectively rendering the brake means active and inactive and means for instantly rendering the braking mechanism ineffective, when the speed falls below the predetermined maximum.

22. A device for controlling the speed of rotation of a revolving door, including a normally inactive brake means actuated by a force independent of the force applied to the door for turning the same and functioning when actuated, to retard the rotation of the door, mechanism operable by rotation of the door at said predetermined speed for rendering the brake means effective and means for instantly rendering the braking mechanism ineffective, when the speed falls below the predetermined maximum.

Signed at New York in the county of New York, and State of New York this 9th day of October, A. D. 1930.
